Primary Examiner — Karen E Kearney*Assistant Examiner* — Cary M Robinson(74) *Attorney, Agent, or Firm* — NSIP Law(57) **CLAIM**

We claim the ornamental design for a display screen or portion thereof with graphical user interface, as shown and described.

DESCRIPTION

The sole FIGURE is a front view of a display screen or portion thereof with graphical user interface showing our new design. The outermost broken line illustrates a display screen or portion thereof and forms no part of the claimed design. The remainder of the broken lines illustrate portions of the graphical user interface and form no part of the claimed design.
